ABSTRACT

Novel N- α -(C_1-C_4 alkyl-benzyl natural fatty acid amides of the formula

wherein R₁ is a fatty acid residue of a naturally occurring oil such as safflower oil etc., and R₂ is alkyl of 1-4 carbon atoms having excellent blood cholesterol lowering effects are provided.

5 Claims, No Drawings

N-SUBSTITUTED AMIDES OF NATURAL FATTY ACIDS

This application is a continuation-in-part of Ser. No. 450,534, filed Apr. 23, 1965, now U.S. Pat. No. 3,551,462.

This invention relates to novel anti-atherosclerosis agents. More particularly, the invention pertains to novel N-substituted natural fatty acid amide derivatives which are useful for lowering the elevated levels of cholesterol or lipids.

Atherosclerosis is an adult disease for which there is no known satisfactory cure. Although the cause for atherosclerosis is not yet known in spite of discussions in the academic circles, it has broadly been recognized that one of the most significant histo-pathological manifestations of atherosclerosis is the deposition of cholesterol or lipids in the blood.

A number of experimental and clinical facts have been reported, which indicate that the reduction of the elevated blood cholesterol or lipid level is considered extremely important for the prevention of atherosclerosis.

The present inventors have found a group of novel compounds which are effective as cholesterol-lowering agents and which are substantially non-toxic.

An object of the present invention is to provide N-substituted natural fatty acid amide derivatives usable as anti-atherosclerosis agents having prominent effects and extremely high admissibility.

Other objects and merits of the invention will be apparent from the following description.

In order to accomplish these objects, the present invention provides novel N- α -alkyl-benzyl natural fatty acid amides of the formula

wherein R_1 is a fatty acid residue of a naturally occurring oil, said fatty acid having an iodine value of at least 50, and R_2 is $\text{C}_1\text{-C}_4$ alkyl, provided that in case the oil is sesame oil, safflower oil, soybean oil or cuttlefish oil, R_2 is $\text{C}_2\text{-C}_4$ alkyl.

The phrase "fatty acid residue of a naturally occurring oil" refers to fatty acid residues of fatty acids which are present in naturally occurring oils. Examples of the naturally occurring oils include vegetable oils, animal oils, etc., such as sesame oil, safflower oil, cuttlefish oil, linseed oil, soybean oil, sunflower oil, corn oil, cottonseed oil, olive oil, peanut oil, flatfish oil, sardine oil, cod oil, menhaden oil, whale oil, residual oil (liver oil from which vitamin A has been removed), peprilla oil and menuke oil, the preferred examples being safflower oil, linseed oil, soybean oil, corn oil, cottonseed oil, sunflower oil, cuttlefish and sardine oil.

The processes for the production of the N-substituted natural fatty acid amides of the present invention naturally vary, for example, depending upon the nature of R_1 and R_2 and the origin of the acid moiety of the amides. Owing to their great number it is not possible to describe all of them in detail, which is in any case unnecessary since they are all based on conventional organic chemistry processes. However, details of typical and suitable processes are given below.

A natural oil is hydrolyzed and the resultant natural fatty acid is reacted directly with an amine of the formula

10 (R_2 is as defined before) in the presence of a dehydrating agent such as a disubstituted carbodiimide compound, in an aqueous or organic solvent.

Typical examples of disubstituted carbodiimide compounds are as follows: dialkylcarbodiimides such as diisopropylcarbodiimide and the like; dicycloalkyl carbodiimides such as dicyclohexylcarbodiimides and the like; and diaryl carbodiimides such as diphenylcarbodiimides; dibenzylcarbodiimides and the like. Of course, carbodiimides other than those specifically mentioned can be employed without any trouble.

20 The condensation reaction between a hydrolyzed natural oil and an amine using a carbodiimide proceeds smoothly at room temperature, but when the reaction is vigorously exothermic, if necessary, it may be allowed to cool.

25 Water and substantially all organic solvents can be employed as solvent. Examples of organic solvents are as follows: ethers such as diethyl ether, tetrahydrofuran and dioxane; esters such as methyl acetate, ethyl acetate, and butyl acetate; ketones such as acetone, methyl ethyl ketone and methyl isobutyl ketone; halogeno alkanes such as chloroform, carbon tetrachloride and ethylene dichloride; and hydrocarbon solvents such as cyclohexane, n-hexane, petroleum ether, gasoline, benzene and toluene. They are employed alone or in the form of a mixture thereof in optional proportions.

The reaction procedure is as follows:

30 The natural fatty acid, the amine and the disubstituted carbodiimide compound, at least one of which is dissolved in a solvent, are mixed at room temperature or under cooling, if required, and the mixture is allowed to stand for 3 to 24 hours while being stirred as necessary. To the reaction mixture is added a small portion of acetic acid to decompose the excess carbodiimide and the urea derivative formed is filtered off to yield the fatty acid amide in the filtrate.

35 Alternatively, a natural oil is reacted with an amine of the aforesaid formula. That is, about 1 mol. of the oil and 1 to 100 equivalent mols of the amine are mixed in the absence or presence of solvents, e.g. alcohols such as methanol, ethanol or the like, aromatic hydrocarbons such as benzene, toluene, xylene or the like, halogenoalkanes such as methylenechloride, chloroform, carbon tetrachloride or the like, alkenes or alkanes such as petroleum ether, benzene, gasoline, ligroin or cyclohexane, and ethers such as tetrahydrofuran, dioxane and the like, or a mixture thereof, and the mixture is subjected to reaction in the absence or presence of a catalytic amount, or equimolar amount to the amine, or an auxiliary condensation agent, such as an alcoholate or an alkali metal, i.e. lithium methylate, lithium ethylate, sodium methylate, sodium ethylate, potassium-t-butylate and the like, or acidic auxiliary agents, i.e. p-toluenesulfonic acid and the like, to yield the amide derivatives. In this reaction, the alcohol formed may be removed from the reaction system.

It is a matter of course that the reaction will proceed even in the absence of solvents and auxiliary agents.

In case of using amines having a lower boiling point, if necessary, an autoclave may be employed, but in case of other amines the reaction mixture is stirred under atmospheric pressure while being heated as necessary, thereby easily yielding the objective amide.

In carrying out the reaction, the mixture of reactants is stirred at a suitable temperature of between room temperature and 400°C for about 3 hours to a month.

If necessary, the reaction is carried on in an atmosphere of an inactive gas such as nitrogen, helium and the like to prevent production of undesirable by-products and coloring, to yield the objective product, which can be subjected to a fractional distillation and recrystallization method using a petroleum hydrocarbon, acetone or the like, or the urea method, to remove saturated fatty acid amides. If alkali alcoholate is used as an auxiliary agent, conjugated double bond isomers are partially obtained. However, the present inventors confirmed that saturated and isomerized fatty acid amides cause no undesirable effect on the human body.

The process for the production of the amides of the invention is described in more detail with reference to the following examples, which are however to be construed for the purpose of illustration only and not as limiting the invention.

EXAMPLES 1-122

General procedure:

a. A natural oil is hydrolyzed in 1N solution of sodium hydroxide in methanol and the resulting natural fatty acid is treated with urea and methanol to remove the saturated fatty acid.

Ten grams of the thus obtained natural fatty acid, an α -alkylbenzylamine and dicyclohexylcarbodiimide are dissolved in benzene and the mixture is allowed to stand overnight at room temperature. Acetic acid is added thereto to decompose the excess amount of dicyclohexylcarbodiimide and the mixture is filtered to separate off the decomposed product. Then the filtrate is washed successively with 5 percent hydrochloric acid, 5 percent sodium carbonate aqueous solution and water, and dried over anhydrous sodium sulfate. Upon evaporation of the solvent, the residue is distilled in vacuo to yield N- α -alkylbenzyl natural oil fatty acid amide.

b. A natural oil and an α -alkylbenzylamine are mixed and stirred in an atmosphere of nitrogen at a temperature of 135°C to 140°C for 40 hours. Then the reaction mixture is distilled in vacuo to yield N- α -alkylbenzyl natural oil fatty acid amide.

According to one of the procedures mentioned above, the following N- α -alkylbenzyl natural oil fatty acid amides are obtained as shown in the following Table 1.

As mentioned above, the N- α -alkylbenzyl natural fatty acid amides of the present invention have excellent cholesterol lowering effects. The effectiveness of the present amides are set forth as shown in the following test examples.

TEST EXAMPLES 1-122

Cholesterol Lowering Effects on Mice

Mice were fed on a special diet which was supplemented with cholesterol and bile acids. Blood cholesterol level of the mice had been elevated to 3 to 6 times the normal level. Each amide compound was well mixed to the specifical diet in 1 percent administration and fed orally to the mice for 10 days. At each dose level, 10 or 20 mice were used and serum total cholesterol levels of the blood serum were measured at the end of the experimental period. One group of mice, in each set of experiment, was given the specifical diet without the test compound and served as control. Mean level of serum total cholesterol of the treated group was expressed as a per cent of that of the control group (blood cholesterol index).

Results are shown in the following Table 2.

1. A compound of the formula

The extremely low toxicities of the instant amides are also an aspect of the present invention.

The cholesterol-lowering agent in this invention may be orally administered. Usually the amount orally administered is 0.1 g. - 20 g. per day for a human adult, preferably 0.5 g. - 5 g. per day, and the administration may be continued for 1-5 months, usually for about 3 months. For example, the amide can be orally administered to a human adult in an amount of 2.0 g. per day for about 3 months. The cholesterol-lowering agent may be employed in any suitable form which is conventional for oral administration. Thus, it may be encased in a capsule, in liquid form, in tablet form, or in powder form. In preparing the agents in these various forms, the active compound may be used as such, without being mixed with a carrier, or mixed with or impregnated in a suitable solid carrier, or it may be mixed with a liquid carrier such as an edible oil, preferably those containing linoleic acid. It is also possible to use a mixture of two or more of the acid amides of the invention. It may also be used as mixed with linoleic acid.

The content of the acid amide of the composition varies depending upon the kind of carrier used, and the content is adjusted so that the amide is administered to a patient within the indicated dosage range.

What is claimed is:

5

10 wherein R₁ is a fatty acid residue of a naturally occurring oil selected from the group consisting of sesame oil, safflower oil, cuttlefish oil, linseed oil, soybean oil, sunflower oil, corn oil, cottonseed oil, olive oil, peanut oil, flatfish oil, sardine oil, cod oil, menhaden oil, whale oil, residual oil, perilla oil and menuke oil, and

15 R₂ is an alkyl group containing 1-4 carbon atoms, with the proviso that when R₁ is a fatty acid residue of sesame oil, safflower oil, soybean oil or cuttlefish oil, R₂ is an alkyl group containing 2-4 carbon atoms.

20 2. A compound according to claim 1, wherein R₁ is a fatty acid residue of safflower oil, linseed oil, soybean oil, cuttlefish oil or sardine oil.

25 3. A compound according to claim 1, wherein R₁ is a fatty acid residue of linseed oil, sunflower oil, corn oil, cottonseed oil, olive oil, peanut oil, flatfish oil, sardine oil, cod oil, menhaden oil, whale oil, residual oil, perilla oil or menuke oil, and R₂ is methyl.

4. A compound according to claim 1, wherein R₁ is a fatty acid residue of sesame oil, safflower oil, soybean oil or cuttlefish oil and R₂ is alkyl of 2-4 carbon atoms.

5. A compound according to claim 1, wherein R₁ is a fatty acid residue of safflower oil and R₂ is alkyl of 2-4 carbon atoms.
